UNITED STATES PATENT OFFICE.

HARLEY C. MOULTON, OF DORCHESTER, MASSACHUSETTS, ASSIGNOR TO ARBETTER FELLING MACHINE COMPANY, OF BOSTON, MASSACHUSETTS, A CORPORATION OF MAINE.

PRESSER-FOOT MECHANISM FOR SEWING MACHINES.

Application filed October 20, 1919. Serial No. 332,028.

To all whom it may concern:

Be it known that I, HARLEY C. MOULTON, a citizen of the United States, and resident of Dorchester, county of Suffolk, State of Massachusetts, have invented an Improvement in Presser-Foot Mechanism for Sewing Machines, of which the following description, in connection with the accompanying drawing, is a specification, like characters on the drawing representing like parts.

This invention relates to improvements in presser foot construction and the principal object thereof is to provide a presser foot which will automatically adapt itself to accommodate various thicknesses of materials and various types of stitching.

More specifically the invention relates to improvements in presser foot constructions for sewing machines having a curved oscillating needle and complementary stitch forming mechanism located above the work support adapted to fell a superimposed layer upon a base layer of material, the base layer being presented to the needle by a bender which is thrust upwardly against the undersurface of the base layer, thus presenting a bight of said layer in the path of the needle and the object of the invention is to provide a yielding presser which will automatically adapt itself to different thicknesses of material and will yield sufficiently under the action of the bender to permit the base layer to be presented to the needle so that a uniform depth of stitching in said layer will be insured, said yielding presser foot being provided with guiding means for positioning the edge of the superimposed layer properly in respect to the needle at all times.

Heretofore a stationary portion of the presser foot and a stationary guide have been used to direct the edge of the superimposed layer into the path of the needle and in order to positively guide the edge of the layer it has been found necessary to restrict the needle throat to so small an area that it was very difficult for the bender to force a light seam sufficiently into the needle throat to enable the needle to penetrate properly the base layer. Where the work comprised heavy cloth or very heavy seams, or had a layer of canvas between the layers of cloth it was quite impossible to force the base

layer sufficiently into the needle throat to enable the needle to enter the base layer.

55

In order therefore to enable heavy cloth to be stitched the needle throat was required to be enlarged by moving the stationary portion of the presser foot and also the guide for the superimposed layer far enough to allow the seams and thicker goods to pass. This resulted in interfering with the proper guiding of the edge of the superimposed layer and practically destroyed the usefulness of the machine for felling lighter materials.

60

65

By providing the presser foot with a yielding shoe to engage the superimposed layer and by securing an edge guide to said yielding shoe means are provided which will permit the bender to thrust the base layer unfailingly into the path of the needle and the yielding shoe and guide will immediately return the superimposed layer into its proper relation to the path of the needle as soon as the bender has been depressed after the stitch in the base layer is made. When a heavy seam or abnormal thickness of cloth is forced into the needle throat the yielding shoe and guide will be forced upwardly sufficiently to allow for the passage of the seam, thereby permitting the soft and pliable portion of the base layer to be presented in the path of the needle and when the bender is retracted the superimposed layer will be automatically forced downwardly by the yielding shoe, and the guide which engages the edge of the superimposed layer will hold said edge in its proper relation to the path of the needle.

70

75

80

85

90

Where heavy work or work containing heavy seams is being sewed the shoe and guide will be continuously reciprocated by the movement of the bender, while in operating upon relatively thin materials the yielding shoe and guide will remain in substantially stationary position.

A further object of the invention is to provide a yielding presser foot which may be removed from operative position either for inspection of the work or to enable other kinds of stitching to be performed upon the work.

Another feature of the invention consists in providing a presser foot with a yieldable shoe having a convexly curved, rearward-

ly converging work engaging surface having near its junction with the heel of the presser foot a receding portion adapted to accommodate the goods which is forced upwardly by the needle during its emergence from the goods whereby the strain upon the goods caused by the passage of the needle therethrough will be eliminated.

Another object of the invention is to provide a presser foot having guiding grooves for the feed dog of an upper feeding mechanism, and a further feature of the invention consists in providing a presser foot of this character with a stripper for detaching the goods from the feed dog as the latter is raised from its engagement with the goods before beginning a return movement in its cycle of operation.

Another feature of the invention consists in providing a presser foot of the character described with a stripper having means for retaining the arm of the bobbin case which prevents the rotation of the latter.

Other objects and features of the invention will more fully appear from the following description and the accompanying drawings and will be particularly pointed out in the annexed claims.

A preferred embodiment of the invention which is illustrated in the accompanying drawings is adapted for use in connection with the well known "Arbetter" type of sewing machines for felling a superimposed layer upon a base layer of material, for padding, and other operations, but it will be understood that my invention may be associated with other types of machines to which it may be applicable.

In the drawings:

Fig. 1 is a front elevation of a presser foot embodying my invention, a portion of one of the screws for securing the same to the head of the machine being shown in section.

Fig. 2 is a side elevation looking toward the minor toe portion.

Fig. 3 is a vertical substantially median sectional view looking toward the inner edge of the minor toe.

Fig. 4 is a top plan view.

Fig. 5 is a bottom plan view.

Fig. 6 is a front elevation similar to Figure 1 but showing the shoe raised to inoperative position.

The presser foot illustrated in the accompanying drawing is adapted to be associated with a sewing machine of the "Arbetter" type, which comprises a bed having a standard rising therefrom carrying an arm which overhangs the bed and has at its end a head supporting stitch forming mechanism including a curved oscillating needle and complementary stitch forming mechanism usually in the form of a rotating hook or loop taker. In the machine to which the particular presser foot illustrated herein is

adapted, the feeding of the goods is performed by an upper feed which is carried by the head, and which forms the subject matter of my co-pending application No. 332,026 filed October 20, 1919.

The preferred form of presser foot which is shown in the accompanying drawings comprises a heel 1 having forwardly extending major and minor toes 2, 3 and a rearward extension 4. Ears 5 and 6 extending upwardly from the major and minor toe portions respectively are provided with screw holes by means of which the presser foot may be secured rigidly to the hook bracket of the sewing machine or to any other suitable support. The major and minor toe portions are respectively provided with grooves 7, 8 extending upwardly from their under surfaces partially through portions of said presser foot adapted to receive and guide the members of the feed dog which are provided with serrated faces for engaging the goods.

The major and minor toe portions are spaced apart to provide the usual needle throat 9 and the front edge of the heel has a recess 10, the lower walls of which are outwardly bevelled or curved to form an extension of the needle throat at the needle path adapted to permit the superimposed layer to pass more readily beneath the presser foot. The clearance thus provided also prevents the needle thread from being clamped between the goods and the presser foot and thereby insures the proper action of the take-up in setting the stitch.

In order to provide the presser foot with throat openings which will adapt the presser foot to operate properly upon goods of various thicknesses a plate 11 is detachably secured by screws 12, to the major toe portion so that plates of different lengths may be substituted in accordance with the size of throat opening required. This plate has the usual rearward extension 13 terminating in front of the needle throat and is provided with an edge guide 14 to direct and sustain the needle during its penetration of the superimposed layer.

The guide 14 also serves to lift the edge of the superimposed layer and in co-operation with the edge guide which embraces the edge of the superimposed layer to direct the edge properly into the path of the needle.

Where plates 11 of different lengths are employed to provide throat openings of different area it is desirable and in fact necessary that the bender shall be adjusted forwardly or rearwardly in the direction of the line of stitching in order that the bender may operate centrally of the throat opening to force the goods into the path of the needle and means for thus adjusting the position of the bender are disclosed in my

pending application No. 332,025 filed October 20, 1919.

The presser foot desirably is provided with a bar 15 which is anchored at its ends 5 in bosses or flanges extending upwardly from the heel portion and acts to prevent the needle thread from being thrown away from the cast off surface of the hook in case a stitch is missed.

10 In order to provide for the passage of seams and other irregularities in the superimposed layer through the needle throat when the goods are advanced by the feeding mechanism and also to provide means enabling the needle properly to engage the base layer when thick material is used in the superimposed layer a presser foot construction is provided which comprises a yielding shoe forming one of the walls of the 15 needle throat, the shoe preferably being provided with a guide which is adjustably mounted upon it.

By reason of this construction a relatively large needle throat opening may be provided 20 without any loss in the efficiency of the guiding mechanism for the edge of the superimposed layer, because if a heavy seam is forced through the needle throat by the bender the yielding shoe and guide will be 25 forced upwardly allowing a sufficient space for the seam and permitting the bender to present the base layer in the path of the needle and when the bender is depressed the superimposed layer will be automatically 30 forced down against the base layer by the shoe and the edge of the layer properly positioned by the guide in the path of the needle when the latter is vibrated laterally to 35 take a stitch in said layer as is common in 40 felling machines of the Arbeiter type.

In the preferred construction disclosed herein the shoe is in the form of a section 16 of the minor presser foot 3 and extends from the inner front end of the presser foot to the 45 front of the heel. The inner edge and lower face of the shoe 16 presents a rounded or convexedly curved surface 17 converging rearwardly toward the needle path. At its rear end and adjacent its junction of the heel 50 the shoe has a receding portion 18 or notch adapted to receive the expanding goods of the superimposed layer which are forced upwardly by the needle as it emerges from said superimposed layer. This clearance enables 55 the goods to be so manipulated by the needle that no strain is imposed upon them which will cause a wrinkling or checking of the superimposed layer.

The shoe 16 as illustrated herein is provided with a laterally extending arm having an inclined edge surface 20, a flat top 21 and a side 22 at right angles to the top. The surfaces 21 and 22 conform to similar surfaces 23, 24 upon the ear 6 of the minor toe portion 60 of the presser foot. A spring 25 which

is secured to the inclined edge 20 by a screw 26 and a dowel 27 has an offset portion 28 adapted to engage the upper edge 23 or the vertical edge 24 of the ear 6. This spring acts to hold the shoe yieldingly against the 70 work when in operative position in Fig. 1 with its end engaging the flat upper edge 23 of said ear.

The shoe is therefore free to yield under the action of the bender when the latter engages a seam or is operating upon thick material. In the latter case the yieldable shoe 16 may have a continuously vibrating movement but will never fail to return the work to its proper position when the bender is depressed and the needle oscillating in its penetrating stroke in the superimposed layer. 75

When the shoe is raised to inoperative position as illustrated in Fig. 6 the end of the spring by engaging the vertical edge 24 of 80 the ear 6 will retain the shoe in such position. The shoe may be provided with a suitable handle for raising the same from operative to inoperative position, a convenient handle being in the form of a plate secured 85 to the inclined surface 20 of the arm 19 by the screw 26 which holds the spring 25 in place.

In order to present the edge of the superimposed layer properly to the needle a guide 90 29 having a curved end 30 adapted to embrace the superimposed layer and converging rearwardly toward the needle path is adjustably connected to the shoe 16 so that it 95 yields with the shoe and maintains its engagement with the edge of the superimposed layer at all times, thereby insuring the 100 positioning of the superimposed layer properly in respect to the needle.

Any convenient means may be provided 105 for securing the guide to the shoe 16. As illustrated herein the guide is provided with an upwardly extending flange 31 having a longitudinally extending slot 32 which receives a pin 33 extending laterally from the 110 arm 19 of the shoe. The flange is adjustably secured in place by means of a set screw 34 extending through the slot 32 and seated in the arm 19. The guide 29 therefore may be adjusted transversely of the line of stitching 115 and may be so positioned as to determine the amount of goods which are forced beyond the needle path by the action of the under face 18 of the shoe 16. Hence the guide may be properly positioned to handle a superimposed layer of any thickness. It also serves to 120 determine the position of the stitching in relation to the edge of the superimposed layer.

The arm 19 of the shoe 16 may be conveniently pivoted upon the cylindrical portion 35 of the set screw 36 which secures the ear 6 of the presser foot to the hook bracket of the sewing machine. 125

Where an upper feeding mechanism is 130

employed to advance the goods during the stitching more or less difficulty has been encountered by reason of the adhesion of the goods to the feed dog as the feed dog is 5 raised from the goods and moved forwardly to its next position to engage the goods. In order to prevent this the present presser foot is provided with a stripper which is adapted to detach the goods from the feed dog as the 10 latter is raised. The stripper which is illustrated herein comprises the plate 37 which is secured by screws 38 to the rear end of the extension 4 and desirably has side flanges 39, 40 extending into recessed portions in the 15 sides of the end of the rearward extension 4 of the presser foot heel. The stripper is also provided with a rearwardly extended member 41 which projects between broadened portions of the feed dog, (as illustrated in 20 my co-pending application aforesaid) and serves to disengage the goods from said broadened portions.

The flanges 39, 40 desirably project a short distance above the upper surface of the rearward extension 4 of the heel, and provide a 25 socket 42 to receive the arm upon the bobbin case which prevents it from rotation. Where, as in the "Arbetter" machines the rotary hook or loop taker is inclined relatively to the bed plate of the machine the 30 upper surface of the extension 4 is inclined as illustrated in Fig. 2, but, of course, it may be made in any form required to co-operate properly with the stitch forming mechanism 35 of the machine to which it is adapted.

It will be understood that the embodiment of the invention disclosed herein is illustrative and not restrictive and that various modifications in form, construction and arrangement of parts may be made within the 40 spirit and scope of the following claims.

Having thus described my invention what I claim is new and desire to secure by Letters Patent is;

45 1. In a presser foot comprising a rigid heel and toes extending therefrom, the space between said toes providing a needle throat; a shoe yieldably mounted on one of said toes adjacent said needle throat adapted to permit 50 seams to pass readily through said needle throat.

55 2. In a presser foot having a rigid heel and major and minor toes extending therefrom, the space between said toes providing a needle throat; a shoe pivotally mounted upon said minor toe located adjacent said needle throat and resilient means operable to retain 60 said shoe in operative or inoperative position.

65 3. In a presser foot for sewing machines for sewing a superimposed layer upon a base layer of material, comprising a rigid heel and toes extending therefrom and spaced apart to form a needle throat; a yieldable shoe on one of said toes located adjacent said

needle throat and a guide on said shoe adapted to embrace the edge of the superimposed layer.

4. In a presser foot for sewing machines 70 for sewing a superimposed layer upon a base layer of material, comprising a rigid heel and toes extending therefrom and spaced apart to form a needle throat; a yieldable shoe on one of said toes located adjacent said needle throat and a guide adjustably secured 75 to said shoe adapted to embrace the edge of the superimposed layer whereby the edge of said superimposed layer may be directed in a predetermined relation to the needle path.

5. In a presser foot for sewing machines 80 for felling a superimposed layer upon a base layer of material, comprising major and minor toes spaced apart to form a needle throat; a shoe pivotally mounted upon said minor toe located adjacent said needle 85 throat, resilient means operable to retain said shoe in operative or inoperative position and a guide having slot and screw connection with said shoe and adjustable thereby 90 relatively to the needle path.

6. In a presser foot for sewing machines for felling a superimposed layer upon a base layer of material, comprising a heel and major and minor toes extending therefrom and spaced apart to provide a needle throat; 95 ears extending upwardly from said toes adapted to be attached by screws to the head of the sewing machine, a shoe having an arm pivotally mounted upon the screw for securing the minor toe to the sewing machine 100 head, a spring secured to said shoe having its end resting upon the surface of the ear of said minor toe portion and operating normally to retain the shoe yieldably in operative position and when the shoe is raised to 105 retain it out of operative position.

7. In a presser foot having a heel and forwardly extending major and minor toes spaced apart to provide a needle throat, a shoe yieldably connected to said minor toe 110 having a rounded work engaging surface convexedly curved and converging rearwardly toward the needle path and operating to force the edge of the superimposed layer toward the needle path, and a receding portion adjacent its junction with the heel of the presser foot to receive the goods which is forced upwardly by the needle as it emerges from the goods.

8. In a presser foot having a heel and forwardly extending major and minor toes spaced apart to provide a needle throat, a shoe yieldably connected to said minor toe having a rounded work engaging surface convexedly curved and converging rearwardly toward the needle path and operating to force the edge of the superimposed layer toward the needle path.

9. A presser foot for sewing machines comprising a heel and major and minor toes 130

provided with grooves extending upwardly from their under surfaces partially through portions of said toes and acting to provide enclosed guideways for a feed dog.

5 10. A presser foot for sewing machines comprising a heel and major and minor toes provided with grooves extending upwardly from their under surfaces to provide guideways for a feed dog and a stripper extending rearwardly from said heel intermediate of said guideways adapted to detach the goods from the feed dog.

11. A presser foot for sewing machines comprising a heel and major and minor toes 15 provided with grooves extending upwardly from their under surfaces to provide guideways for a feed dog and a stripper detachably secured to said heel intermediate of said guideways having a narrow rearwardly 20 extending member adapted to detach the goods from the feed dog.

12. A presser foot for sewing machines comprising a heel having a rearward extension, a forwardly extending toe and 25 means for securing the said presser foot to the head of the sewing machine, a stripper detachably secured to the rearward extension of said heel and having sides extending upwardly beyond the upper surface thereof 30 to provide a holder for the tail of the arm

of the bobbin case, and a rearwardly extending stripping member having its lower surface in the same plane as the lower surface of the heel.

13. In a presser foot having a rigid heel 35 and major and minor toes extending therefrom, the space between said toes providing a needle throat; a shoe pivotally mounted on said minor toe located adjacent to and forming a section of one of the walls of the 40 needle throat, resilient means operable to retain said shoe in operative or in inoperative position and a handle connected to said shoe for moving the same into and out of operative position.

45 14. In a presser foot having a rigid heel and major and minor toes extending therefrom, the space between said toes providing a needle throat, a shoe pivotally mounted upon said minor toe located adjacent said 50 needle throat and resilient means for retaining said shoe in operative position and a plate detachably secured to said major toe and providing a needle guide and forming the front wall of the needle throat, whereby 55 by substituting plates of different length the throat opening may be varied.

In testimony whereof, I have signed my name to this specification.

HARLEY C. MOULTON.
